GOLF CLUB HEAD

Rowland M. Barrett, R.F.D. Job's Pond, Portland, Conn.

Filed July 25, 1961, Ser. No. 66,058

Term of patent 14 years

(Cl. D34—5)

FIG. 1 is a side elevational view of a golf club head showing my new design.

FIG. 2 is a front elevational view thereof.

FIG. 3 is a perspective view thereof.

The broken line showing of a shaft is for illustrative purposes only.

I claim:

The ornamental design for a golf club head, as shown and described.
